(57) **CLAIM**

The ornamental design for an animal training device, as shown and described.

DESCRIPTION

FIG. 1 is a top view of an animal training device, shown in use, attached to a leash.

FIG. 2 is a perspective view of the animal training device.

FIG. 3 is a top plan view of the animal training device, the bottom plan view being a mirror image thereof.

FIG. 4 is a front elevation of the animal training device.

FIG. 5 is a rear elevation of the animal training device.

FIG. 6 is a left elevation of the animal training device.

FIG. 7 is a right elevation of the animal training device.

FIG. 8 is a second perspective view of the animal training device; and,

FIG. 9 is a sectional view of the animal training device, taken along line 9—9 of FIG. 5.

The broken lines in FIG. 1 depict an attachable leash and are illustrative of environment and are not intended to form a part of the claimed design.
